UNITED STATES PATENT OFFICE.

S IRMA SMITH, OF MEMPHIS, TENNESSEE.

CATTLE-GUARD.

1,314,910.

Specification of Letters Patent.

Patented Sept. 2, 1919.

Application filed March 8, 1919. Serial No. 281,482.

To all whom it may concern:

Be it known that I, S IRMA SMITH, a citizen of the United States, residing at Memphis, in the county of Shelby and State 5 of Tennessee, have invented a new and useful Cattle-Guard, of which the following is a specification.

This invention has reference to cattle guards, and its object is to provide a guard 10 of light, safe, cheap, durable and fire-proof construction which may be readily collapsed for shipment, and when in place in the track will effectively prevent the passage of cattle along the track but will not trap and 15 hold the cattle like some devices which have been put in use.

The guard comprises metallic interchangeable sections to be introduced between the ties of the track, and triangular wooden top 20 pieces for the ties both between and beyond the rails, all so arranged that the cattle can back out but cannot go forward, whereby the cattle will be kept from walking along the track. The guard may be in most part 25 made of sheet metal at the shop stamped or rolled into shape and sent out to the section foreman to install by simply placing 30 the guard between the standard ties. The guard is so constructed that no part projects above the ties making it impossible for dragging brake beams to catch in the guard or cause damage to the guard in any way.

The invention will be best understood 35 from a consideration of the following detailed description taken in connection with the accompanying drawings forming part of this specification, with the understanding, however, that the invention is not confined to any strict conformity with the showing 40 of the drawings, but may be changed and modified so long as such changes and modifications mark no material departure from the salient features of the invention as expressed in the appended claims.

45 In the drawings:

Figure 1 is a plan view of a short length of track provided with the guard.

Fig. 2 is a section on the line 2—2 of Fig. 1.

50 Fig. 3 is a section on the line 3—3 of Fig. 1.

Fig. 4 is a perspective view of one of the guard sections in the collapsed position.

55 Fig. 5 is a perspective view of one end of a section of the guard showing a somewhat modified form.

Referring to the drawings, there are shown rails 1 and ties 2 which may be taken as indicative of the rails and ties of an ordinary railroad track.

Fast on the top of the ties between the rails being secured thereto in any preferred manner are wooden strips 3 and beyond the rails are wooden strips 4, these strips being of angular or wedge shape, with the angle 60 uppermost, so as to present contracted and insecure footing to cattle, wherefore cattle will avoid stepping on the ties in an effort to travel along the track, or if they should step thereon will immediately back out and 65 retrace their steps. No novelty is claimed for this element of the invention. It will be understood that equivalent means may be provided, but the triangular strips are found to be efficient for the purpose.

70 Referring to Fig. 1 of the drawings, there is shown a series of four metallic structures forming the guard and constituting the essential feature of this invention. These guard sections are alike and therefore interchangeable, and may be of any number desired to form a complete protection.

75 Each metallic structure or section is inserted between the ties so as to rest upon the road bed 2, beneath the plane of the rails and comprises a series of plates 5, each of which may be made of sheet metal having side flanges 6, and these plates are connected together by bars or strips 7, 8, respectively. The connecting means shown 80 comprise rivets or pivot pins or bolts 9 traversing the strips 7 and 8 and the flanges 6 near opposite extremities of said flanges 6, so that by moving the strips 7 and 8 lengthwise in one direction the plates 5, 95 which are arranged parallel one to the other, are separated, and when moved in the other direction the strips 7 and 8 are brought flat together, thereby collapsing the unit made up of the plates 5 and the strips 7 and 100 8 as shown in Fig. 5. At the ends of each section a brace 5^a is provided extending from the lower pivot of one plate to the upper pivot of the next adjacent plate so as to keep the section from collapsing. The 105 ends of the brace are detachably mounted in place so that upon releasing either end the collapsing of the sets of plates forming the section may be effected. The arrangement is such that when the plates 5

110 are moved apart by the parallel motion provided, and a section or unit is lodged

between two adjacent ties, the tops of the plates are about on a level with the tops of the ties, while the width of the plates causes the unit or section to occupy the entire space 5 between two adjacent ties from approximately one end to the other of the ties as shown in Fig. 1. When the strips 7 and 8 are spread apart, thus bringing the plates toward the erect position, and the unit or 10 section occupies approximately all the space between the ties, the top of one plate is about vertically over the bottom of the next succeeding plate. By properly proportioning and spacing the plates, an animal is not at 15 all liable to catch its legs in between the plates, but must plant its feet on the upper edges of the plates which provide an uncertain and insecure footing not conducive to a desire for further forward travel. The 20 slant of the plates is reversed in each alternate section as shown in Fig. 1, and this contributes to the difficulty of the animal walking on the track.

The top edges of the plates may be made 25 toothed or serrated, as indicated at 10 in Fig. 5, or may be smooth, as indicated in the other figures. Fence sections 11 may be provided to prevent the cattle from passing about the cattle guard, but this feature 30 forms no part of my invention.

It has been found, in practice, that the space between five standard ties is sufficient to prevent stock from jumping the cattle guards. This would require the use of four 35 sections or units, but if additional sections be desired they can easily be added. The best positions for the plates 5 when installed is at an inclination of about 45°, but such particular angle is not obligatory.

40 The gage of metal used is of course sufficient to withstand conditions of use and the metal may be protected by galvanizing or painting, sheet steel being best adapted for the purpose. The collapsibility of the 45 units or sections is not only advantageous for shipping but for placing and withdrawing the units, and the provision of the braces at the ends prevents collapse when the units are in place should an animal step on any 50 part thereof.

The units or nests of plates each extends crosswise of the track, causing the plates to be presented with their upper edges lengthwise of the rails so that an animal 55 in attempting to pass the guard will find painful although not harmful footing, for the plates should be close enough together to prevent catching and locking the feet of the animal between them. Moreover, the 60 units are all identical and therefore interchangeable so their number may be as great or small as desired, and the units may be initially made up in large quantities.

The strips 3 have their ends beveled, as 65 shown at 12, to avoid interference with the

flanges of the car wheels. The strips 4 have their outer ends undercut, as shown at 13, to accommodate the gates 11 when set in an outwardly flaring position, and the gates 11 have braces 14 for holding them in such 70 flaring position, the undercuts 13 contributing to holding and steadyng the gates.

It is not obligatory that the units or nests of plates 5 be made collapsible or even be joined by the side bars 7 and 8 in the manner shown, for other arrangements may be provided whereby the plates are, in the installed position, arranged between the ties in a series extending lengthwise of the ties or crosswise of the track, and so spaced 80 apart as to present an insecure footing of such small area as to obstruct the passage of an animal attempting to walk thereon without doing any real harm to the animal. The triangular strips 3 and 4 are advantageous in conjunction with the plates 5 in contributing to the insecurity of footing on the ties. The units, when installed, have the upper edges of the plates 5 in substantial alinement lengthwise of the track. 85

The metallic plates being connected together may be removed bodily when making repairs to the roadbed or cleaning out snow.

The depth of standard ties is about eight or nine inches, consequently the depth of 95 the metallic structures is not sufficient to trap stock and hold it, but stock can release itself and get out of the guard though it cannot go forward or over the guard.

What is claimed is:—

1. A cattle guard provided with complete sections or units for introduction between adjacent ties of a railroad track and to be supported upon the road bed below the rails, each section or unit being wholly independent of each other and having a series of spaced inclined plates which are arranged lengthwise of the track, said sections or units filling the space between the ties and extending along the same and accessible at 100 the outer sides of the track and made separately removable.

2. A cattle guard provided with complete sections or units for introduction between adjacent ties of a railroad track, being 115 mounted upon the road bed below the rails, each section or unit being wholly independent of each other and having no connection with the ties or rails, and comprising a series of plates and connecting means therefor sustaining the plates, when in installed position, at an inclination, with the plates extending lengthwise of the track and in longitudinal alinement, and not projecting above the plane of the upper face of the ties, said 120 sections or units filling the space between the ties and bearing against the sides of the latter and extending along the same and accessible at the outer sides of the track, each section or unit being separately removable. 125

3. A cattle guard for railroad tracks, comprising a plurality of complete sections or units for introduction between the adjacent ties of the track, and extending below the rails and filling the space between the ties and resting upon the road bed, each section or unit comprising a series of inclined plates, and bars connecting the plates at the top and bottom in parallel relation, with the plates extended lengthwise of the track and in longitudinal alinement, and said bars bearing against the sides of the ties, whereby the upper edges of the plates are presented adjacent to the bottoms of the rails and beneath the tops of the ties, and thus provide an insecure footing for animals.

4. A cattle guard for railroads, comprising a plurality of sections or units each made up of a series of spaced parallel inclined plates with edge flanges on opposite sides, and upper and lower bars pivotally connecting the plates at the flanges to hold the plates in inclined position between adjacent ties, with the plates extended lengthwise of the track and in longitudinal alinement.

5. A cattle guard provided with complete independent sections or units for introduction between adjacent ties of a railroad track to rest upon the road bed, said sections or units filling the space between the ties and extending along the ties substantially throughout the length of the latter so as to be accessible at either of the ends of the ties, and being removably mounted in place, each section or unit being separately removable from either side of the track.

6. A cattle guard provided with sections or units for introduction between adjacent ties and transversely beneath the rails of a railroad track, each section or unit comprising a series of inclined plates, and connecting means therefor sustaining the plates in installed position at an inclination, with the plates extended lengthwise of the track, said sections or units filling the space between the

ties, the opposite ends of the sections projecting beyond the opposite sides of the rails so that each section or unit is accessible and removable at either side of the track.

7. A cattle guard provided with sections or units for introduction between adjacent ties of a railroad track, each section or unit comprising a series of plates, and connecting means therefor sustaining the plates when in installed position at an inclination, with the plates extended lengthwise the track, the connection between the plates and said connecting means permitting the plates to be collapsed one upon another.

8. A cattle guard provided with sections or units for introduction between adjacent ties of a railroad track, each section or unit comprising a series of plates, and bars connecting the plates and sustaining them when in installed position at an inclination, with the plates lengthwise the track, the bars and plates being pivotally connected so that the entire section or unit may be collapsed, and means for locking the plates from movement on their pivots when the sections are in position.

9. A cattle guard provided with sections or units for introduction between adjacent ties of a railroad track, each section or unit comprising a series of plates, upper and lower bars connecting the plates and sustaining them when in installed position at an inclination, with the plates arranged lengthwise the track, the bars and plates being pivotally connected so that the entire section or unit may be collapsed, and braces connecting the upper and lower bars at each end to hold the section from collapsing when in position.

In testimony that I claim the foregoing as my own, I have hereto affixed my signature.
